AIR CONDITIONER

Albert M. Highhouse, Spokane, Wash., assignor of
one-half to Carter J. Carlsen, Spokane, Wash.

Application December 8, 1937, Serial No. 178,798

2 Claims. (Cl. 183—22)

This invention relates to an air conditioner and it is one object of the invention to provide a device of this character adapted to be associated with a hot air furnace serving as a distributor and by means of which air may be moistened and dust, lint and other impurities removed therefrom. It will thus be seen that the air when delivered to the furnace will be moist and free from impurities and in such condition delivered to rooms of a building through the pipes and registers of the hot air furnace.

Another object of the invention is to provide a device of this character wherein water is fed to a pipe extending transversely of walls of an air tunnel, the pipe being provided with discharge nozzles through which fine sprays are discharged in such relation to the tunnel and each other that they form a mist through which the air is driven by an electric fan and thus the air thoroughly moistened.

It is another object of the invention to provide an approved arrangement of baffles or louvers which serve to catch and remove dust and lint from the air after the water treatment.

Another object of the invention is to so construct the baffles or louvers that drops of water striking them will be caught and delivered to troughs at their lower edges and thus permit the water to flow from the baffles and into a water pan or sump formed in the lower portion of the air tunnel.

It is another object of the invention to provide improved means for mounting the baffles or louvers and not only firmly support them in their proper position in the air tunnel but also permit frames carrying the baffles to be bodily withdrawn from the air tunnel when cleaning or repairs are necessary.

The invention is illustrated in the accompanying drawings, wherein:

Figure 1 is a view showing the improved air conditioning apparatus in longitudinal section upon a vertical plane,

Figure 2 is a vertical sectional view taken transversely through the air tunnel along the line 2—2 of Figure 1,

Figure 3 is an enlarged view in elevation of the water spraying means,

Figure 4 is a fragmentary sectional view taken along the line 4—4 of Figure 2, and

Figure 5 is an enlarged sectional view of one of the spraying nozzles of the water-spraying device taken along the line 5—5 of Figure 1.

The body of this air conditioner may be formed of sheet metal or any other desired ma-

terial and has a horizontally extending portion or tunnel 2 which is rectangular in cross section, as shown in Figure 2, and may be of any desired height and width. A vertically extending portion or tower 3 extends upwardly from the outer end of the tunnel 2 and at its top is closed by a cover or upper wall 4. Pipes 5 extend from the side walls of the tower and are to extend to rooms of the house or other building in which the air conditioner is installed so that air may be withdrawn from the rooms by a fan 6 and after being treated returned to the rooms through pipes leading from the hot air furnace 7 which serves as a distributor for the air. While it has been stated that the distributor is a hot air furnace of a conventional construction, it is to be understood that any distributor of a conventional or special construction may be used and that, if so desired, cooling means may be provided in order that the air may be cooled during hot weather before it is distributed to the rooms of the building. By employing a hot air furnace as the distributor special equipment for distributing the air to the rooms of the building will not be required and the air may be delivered in a heated condition. An opening 8 is provided at the front of the body in order that access may be had to the interior thereof when cleaning or repairs are necessary and this opening is normally closed by a closure plate or door 9 which is detachably held in closing relation to the opening in any desired manner.

The fan 6 may be of any size desired and has its shaft 10 rotatably mounted in the bearing 11 at the upper end of a bracket 12 which extends vertically and is provided at its bottom with a base 13 secured upon a bolster 14. This bolster rests upon the bottom of the tunnel and extends the full width thereof, a sheath 15 being provided to shield the bolster from water and define a pocket 40 in which the bolster is fitted and in addition provide a wall 16 which together with a wall or flange 17 at the inner end of the tunnel to define a water pan or sump extending substantially the full length of the tunnel and adapted to receive 45 water which is sprayed across the forward portion of the tunnel during operation of the air conditioner. An outlet pipe 18 leads from a side wall of the tunnel and is located at such a height above the bottom of the tunnel between the end 50 walls 16 and 17 of the water pan that water will escape through this pipe instead of overflowing at ends of the water pan. The base 13 of the fan projects from the bolster and its sheath with its projecting end portion supported upon a block 19 55

and serving as a platform upon which is mounted an electric motor 20. This electric motor carries a pulley 21 upon its shaft and the shaft of the fan carries a larger pulley 22 so that, when the motor 5 is in operation, rotary motion may be transmitted from the motor shaft to the fan shaft at a reduced rate of speed through the medium of a belt 23 which is trained about the pulleys. This is clearly shown in Figure 1, and referring to this 10 figure, it will be seen that during operation of the air conditioner the fan will exert suction to draw air through the pipes 5 and downwardly through the tower 3 to the front end of the tunnel 2, and this air will be forced through the 15 tunnel and into the distributor or hot air furnace 1, from which it will pass through the usual distributor pipes and out through registers into rooms of the building.

The air which is driven through the tunnel 20 from its front end toward the distributor is to be moistened, and in order to do so, there has been provided a water pipe 24 leading from a suitable source of supply and having one end extending into the tunnel and attached to a T-coupling 25 25 at one corner of a rectangular pipe frame or conduit 26 which fits snugly within the tunnel against walls thereof and extends transversely of the tunnel. A suitable number of threaded necks 27 extend from the pipe frame or rectangular 30 conduit and each of these necks carries a nozzle 28 from the outer end of which projects a nipple 29 formed with a bore 30 and a small outlet opening or perforation 31 through which water 35 may be discharged in a fine spray. A plug 32 which is tapered as shown clearly in Figure 5 has wedging fit in the bore of the nipple and serves to regulate the quantity of water which 40 may flow from the nozzle into the nipple. By replacing the plug with others of larger or smaller dimensions the quantity of water discharged from the nipple can be regulated. While the necks and nozzles carried thereby have been shown provided upon the lower cross arm and the vertical side arms of the rectangular pipe frame or conduit 45 45, it will be understood that they may also be provided upon the upper cross pipe of this pipe frame if so desired and also that the number of necks and nozzles may be increased if found necessary or desirable. The water when discharged from the nipple forms a plurality of 50 sprays which merge with each other to create a water curtain through which the air is forced by the fan. Therefore, the air will be moistened and also any dust, lint or other foreign matter 55 will be moistened and caused to readily adhere to baffles or louvers which are interposed in the tunnel between the water frame and the distributor.

The louvers or baffles are arranged in groups 60 spaced from each other longitudinally of the tunnel and indicated in general by the numerals 33 and 34. These groups of baffles are set in place and removed through an opening 35 formed in the top of the tunnel, and when the cover 36 65 for this opening is set in place it rests upon tracks 37 formed of angle metal and secured against side walls of the tunnel with their horizontal flanges projecting laterally from the side walls. The end portions of the tracks extend 70 under portions of the top wall of the tunnel at ends of the opening, and since these tracks project from one end of the opening quite a distance, as shown in Figure 1, the cover, when grasped by its handle 38 and set in place, may be slid longitudinally of the tunnel until the cover passes 75

entirely through the opening and rests upon the tracks for its entire length, after which the cover may be slid longitudinally towards the forward end of the tunnel and its forward end moved under the top wall and make contact with the abutment tongues 39 at the front ends of the tracks. It will thus be seen that the cover may be very easily applied or removed and that, when it is in place, the opening 35 will be completely closed. Each of the groups of baffles is provided with a 10 frame 40 formed of sheet metal and provided with side flanges 41 for engaging in tracks 42 formed by strips of angle metal 43. The upper ends of the tracks 42 register with slots formed in the horizontal flanges of the supporting strips 37, and when a frame is grasped by its upper cross bar 15 it may be very easily inserted or removed. When the frame is in place with its side flanges engaged in the tracks between the strips 43 and its lower cross bar resting upon the bottom of the tunnel, it will be firmly braced and maintained in 20 an upright position in the tunnel. The upper cross bars of the two frames serve not only as hand-holds by means of which the frame may be grasped and inserted or removed but also constitute supporting strips extending transversely across the opening 35 and engaging the under face of the cover to support and brace the cover when the cover is in place. The baffle plates or louvers 44 constituting the group 33 extend at 25 an incline opposite to that of the baffle plates or louvers constituting the group 34, and while each group or set has been shown consisting of three plates or louvers, it is to be understood that any 30 number desired may be provided in accordance 35 with the dimensions of the air conditioner. The baffle plates or louvers 44 and 45 are formed with side flanges 46 and 47 through which rivets are passed to secure the frame to side bars of the frame 40, and lower portions of the sheets of 40 metal from which the baffle plates or louvers are formed are bent to form troughs or channels 48 and 49 serving to catch water which runs 45 downwardly along the faces of the baffles. Cross strips 50 which may be referred to as deflector 45 plates extend across the frames immediately below side edges of the upper cross strips thereof to block the upper portions of the frames and thus cause air to be properly directed through the frames as it moves along the tunnel towards 50 the distributor 1.

When this air conditioner is in use, it is disposed laterally of the hot air furnace or equivalent distributor 1 and the open outer or rear end of the tunnel secured against the hot air jacket 55 of the furnace in any desired manner about an opening formed therein which may be a specially provided opening or the opening with which the fresh air pipe is usually connected. The pipes or conduits 5 are extended from the upper portion of the tower 3 to rooms of the building 60 where they terminate in registers so that air may be withdrawn from these rooms or if the device takes the place of the usual fresh air pipe of a hot air furnace a pipe 5 of the proper dimensions 65 may be secured about a window opening or other source of outside air. The motor 20 is set in motion to operate the fan and as the fan rotates air will be drawn through the pipes 5 and the tower 3 and forced through the tunnel towards 70 the distributor. A valve for controlling flow of water through the pipe 24 will be opened and water will be discharged in sprays from the nipples of the nozzles 38 to form a curtain of spray through which the air passes. The fine 75

water spray will moisten the air and also force any dust or lint floating in the air and as the air strikes the baffle plates or louvers 46 of the group 43 and is deflected upwardly by these plates water will be removed from the air by striking the plates and any dust or lint will have a tendency to stick to the plates and move downwardly along the same with the water to the troughs or gutters 48 through which the water flows until it reaches ends of these troughs and drips down into the water pan or sump formed at the bottom of the tunnel. The air which is directed upwardly by the baffle plates 44 passes from these baffle plates to the group 34 and upon striking the baffle plates or louvers 45 it will be directed downwardly along the sloping faces of these baffle plates and substantially all of the water and dust or lint which the baffle plates 44 fail to remove will be removed by contact with the plates 45 and flow downwardly along the plates 45 to the trough or gutters 49 through which the water flows until it reaches the ends of these gutters and drips down into the water pan of the tunnel. The air which has been freed of dust and lint will retain sufficient moisture to be delivered to the distributor as moist air and this air will pass from the distributor through the usual air pipes or special air pipes to registers in rooms of the building. It may be delivered either as warm air or if cooling means has been provided in the distributor the air may be delivered in a cooled condition to the rooms and thus serve to cool the rooms as well as furnishing fresh clean air to the same.

Having thus described the invention, what is claimed as new is:

1. In an air conditioner, a horizontally extending tunnel open at its ends and adapted to have one end connected with a distributor, a fan at the other end of the tunnel for forcing air through the tunnel, means in the tunnel adjacent the fan for creating a transversely extending curtain of water mist, said tunnel having an opening in its top between the means for creating the water mist curtain and the first-mentioned end of the tunnel, strips carried by side walls of the tunnel and constituting vertical tracks having their upper ends exposed through

the opening in the top of the tunnel and sets of baffles fitted into the tunnel through the opening in the top in spaced relation to each other longitudinally of the tunnel, each set of baffles consisting of a frame insertable and removable through the opening in the top of the tunnel and having its side portions slidably engaging companion tracks, and baffle plates extending transversely of the frame and tunnel and having flanges secured against side portions of the frame, the baffle plates being disposed at a vertical incline with the baffle plates of one set extending at an angle opposite to the angle of the baffle plates of the other set, and a cover for the opening in the top of the tunnel removably held in place.

2. In an air conditioner, a horizontally extending tunnel open at its ends and having one end adapted to be connected with a distributor, an opening being formed in the top of the tunnel intermediate its length, strips extending along sides of the tunnel longitudinally thereof at opposite sides of the opening and projecting under the top of the tunnel a tends of the opening, a cover for said opening having side portions resting upon said strips and its end engaging under portions of the top of the tunnel at opposite ends of the opening, the cover being slidable along said strips to permit insertion and removal of the cover, a fan for forcing air through the tunnel towards the distributor engaging end thereof, tracks extending vertically at sides of the tunnel in spaced relation to ends of the opening, an open frame fitted into said tunnel through the opening in the top thereof and having side flanges engaging said tracks to slidably mount the frame for insertion and removal through the opening and support the same in a vertical position, baffle plates extending transversely across said frame one above another and disposed at a vertical incline and having flanges at their ends secured to side portions of the frame, the upper portion of the frame being substantially flush with said strips and constituting means extending transversely in the tunnel for bracing the cover between side walls of the tunnel.

ALBERT M. HIGHHOUSE.
